UNITED STATES PATENT OFFICE.

JAMES H. VAN DE WATER, OF AUBURN, NEW YORK.

WASHING-MACHINE.

SPECIFICATION forming part of Letters Patent No. 230,367, dated July 20, 1880.

Application filed June 2, 1880. (No model.)

To all whom it may concern:

Be it known that I, JAMES HENRY VAN DE WATER, a citizen of the United States, residing at Auburn, in the county of Cayuga and 5 State of New York, have invented new and useful Improvements in Washing-Machines, of which the following is a specification.

My invention relates to improvements in that class of washing-machines in which the clothes 10 are washed by a pounding action and in which the pounding device is clamped to a wash-tub; and the objects of my improvements are to provide a more effective and durable connection of the pounding device with the tub-clamping 15 standard, and to provide for a more effective action of the pounder, in connection with the action of the air upon the clothes.

These objects I attain by the construction shown in the accompanying drawings, in 20 which—

Figure 1 represents a view, in perspective, of the entire machine; Fig. 2, a vertical section of the same; Fig. 3, a bottom view of the pounder; Fig. 4, a horizontal section of the pounder on the line $x x$ of Fig. 2; and Fig. 5, a detail sectional view of the yielding-face part of the cup, showing its slotted connection with the center tube of the cup.

The pounding device is carried by a standard, a , which is clamped to the side of the tub, being for that purpose provided with spreading hook-feet b and a clamping-button, c , secured in a slot, d , in said standard and adapted to be clamped over the top of the tub by a 30 thumb-screw. The standard terminates in a bifurcated davit-head, a' , which forms the bearings $e e$ for a short shaft, on which an eccentric, f , operates between the davit-arms to give the proper action to the pounder by a 35 strap-connection, g , therewith. A suitable distance above the tub, and between it and the davit-head, the standard is provided with a guide-box, h , formed upon a horizontal arm, h' , to receive and support a vertical tube, i , 40 which carries the pounding-head. This tube is united to the eccentric strap-connection g by means of a rod, j , which, extending into the tube i , is jointed to the lower end of the eccentric-strap connection by a pin, and it is by 45 this construction that the pounder can be adjusted to the quantity of clothes in the tub by 50

adjusting the rod j into or out of the tube i , and clamping the two firmly together by the screw k , at the top of said tube and above the guide-box.

By this construction the davit-head gives a firm support for the eccentric, the operation of which is effected by the crank-handle l on its shaft, while the long bearing of the box h supports and guides the tubular connection of the pounding-head with the eccentric, and it is by reason of these two supports upon a single clamping-standard that compactness and durability of the operating parts are obtained, in connection with the adjustable rod in the tube 65 above the guide-box, for varying the throw of the pounder according to the quantity of clothes in the tub. The action of the eccentric gives a regular pressing and lifting movement to the pounder and avoids the splashing incident to 70 hand-pounding, the action of a crank, or of a sudden descent of the pounder by a spring.

The pounder consists of two parts, an outer one, partly conical and partly cylindrical, and forming the air-compressing cup, and an inner 75 part, forming the pounding-face; and both these parts are carried by the tube i , and upon which the pounding-face has an independent reciprocating movement. The outer-cup part, m , has a perforated partition, m' , which forms a 80 conical-top air-chamber, m^2 , and a cylindrical bottom chamber, m^3 , within which the pounding-face part n operates. This part n consists of a perforated disk with a rising curb or hoop, r , by which it forms a close joining with 85 the inner wall of the cylindrical part of the cup.

From the disk rise four or more tubes, s , which, passing through the perforations in the partition m' , terminate with their open ends in 90 the conical chamber m^2 , while the outer ends of these tubes open into hollow ribs t , secured to and crossing the outer side of the face part n , and which, besides being open at their outer ends, are provided with perforations t' , the 95 purpose of which is to allow the compressed air to escape from the conical chamber and pass down through said tubes and out of the hollow ribs into the clothes when the pounder is forced down and the ribbed part is forced, 100 by the resistance of the clothes, up into the cylindrical chamber. This ribbed face part n

has a central sleeve, *u*, which fits upon the lower end of the central tube, *i*, and a slot, *u'*, in said sleeve limits, by means of a pin, *v*, the reciprocating movement of the ribbed face part *n* under the action of the pounder.

The air-conducting tubes are provided with surrounding coiled springs *w*, which, pressing upon the partition *m'* of the cup and upon the ribbed face part, force out the latter upon the upstroke of the pounder. The face part also has perforations *n'* between the ribs, which open directly within the bottom chamber, *m*³, and the tubes, opening into the upper chamber, serve to distribute the air under force evenly into the clothes at the surface, which acts directly upon them.

As the action of the ribs by their inclined sides is to press the clothes in gutters, the air spurting out from the perforations in the bevelled sides of the ribs gives a good effect in cleaning the clothes uniformly, the air being forced out of the top chamber into and out of the ribs by the action of the pounder upon the clothes. The pounder is of a diameter to nearly fill the tub, and by the adjustment of the connecting-rod within the tube *i* the pounder can be set to give more or less pressure upon the clothes and to work the same upon varying quantities of clothes, washing them evenly and thoroughly by pressure, suction, and air action.

I may use the washer in a boiler by a handle when the clothes are put to boiling.

I claim—

1. The combination, in a washing-machine, of the tub-clamping standard having a bifurcated davit-head, *a'*, and a guide-box, *h*, with the operating eccentric pounder with a crank-handle and mounted upon the forks of the davit, and the pounding-cup, the tube *i* whereof is supported in said guide-box at a point below the connection of the eccentric-strap with the said pounder-tube, substantially as herein set forth.

2. The combination of the pounding-face part *n*, having the hollow perforated ribs *t*, the hoop or curb *r*, and the vertical tubes *s*, with the cup part *m*, having the upper and lower chambers, *m*² *m*³, and the springs *w*, said tubes communicating with the upper chamber and with the hollow perforated face-ribs, substantially as and for the purpose described.

In testimony whereof I have hereunto set my hand in the presence of two subscribing witnesses.

JAMES HENRY VAN DE WATER.
